WIRE BENDING BLOCK

John M. Moulthrop, Cleveland, Ohio

Application September 4, 1956, Serial No. 42,819

Term of patent 14 years

(Cl. D55—1)

FIG. 1

FIG. 2

Figure 1 is a plan view of the wire bending block showing my new design; and

Figure 2 is a side elevation of the same.

I claim:

The ornamental design for a wire bending block, as shown.
